ANTENNA ARRANGEMENT FOR THE RECEP-
TION OF SHORT ELECTRICAL WAVESAlbrecht Gothe, Berlin, Germany, assignor to
Telefunken Gesellschaft für Drahtlose Tele-
graphie m. b. H., Berlin, Germany, a corpora-
tion of GermanyApplication April 28, 1932, Serial No. 607,913
In Germany April 28, 1931

1 Claim. (Cl. 250—11)

Directional antenna arrangements for the reception of short electromagnetic waves are known in the prior art which comprise an antenna and a reflector part. In order to insure complete shielding of radiations arriving from the rear, it is necessary to insure accurate regulation of the amplitude and phase relations between the currents picked up by the antenna and the reflector. The compensator schemes used therefor are greatly a function of the frequency, and they insure unilaterally directional reception only for a very definite wave-length. In the arrangements heretofore used the means provided for regulating the phase and the amplitude are disposed directly at the antenna, whence the incoming currents are conducted to the receiver by way of an energy line.

According to the present invention, both the antenna as well as the reflector are provided each with an energy feed line (or downlead) so that amplitude and phase regulation for the antenna and the reflector current may be effected directly at the receiver. As a result it is feasible to insure perfectly unilateral directional reception inside a relatively large wave band.

Referring to the drawing, Figs. 1 and 2 show circuit arrangements embodying the principles of the present invention. Fig. 1, A and R denote the antenna and the reflector, L_A and L_R are the two transmission lines, P_A and P_R are means for phase regulation, and K_A and K_R the means adapted to amplitude regulation of the antenna and the reflector currents, while E is the receiver.

In order to obtain the same input potential throughout the entire frequency band it is recommendable to terminate the two energy feed lines L_A and L_R by such ohmic resistances W_A and W_R that no standing waves are likely to be produced upon the same.

The arrangement is also useful for the simultaneous reception of several waves. All that is necessary for this purpose is to interpose non-reactive coupling units or links between the energy-feed lines and the receivers, this, as well known from the prior art, being possible, for instance, by means of thermionic tubes.

A fundamental case covering this scheme is shown in Fig. 2. Thermionic tubes are connected in parallel relation to the resistances W_A and W_R . In the case of the illustration any unsymmetric energy feed line or downlead has been assumed of which one conductor is earthed. When using symmetric energy lines it is necessary to provide symmetric "push-pull" circuit schemes. Fundamentally speaking, simultaneous reception of several waves is feasible also without the terminal resistances W_A and W_R . Since antenna and reflector are equivalent it is possible to receive simultaneously from opposite directions, and it is immaterial in this connection whether the incoming waves are equal or dissimilar.

I claim:

The combination in a radio receiving system of a plurality of antennae, a receiver, individual energy feed lines coupling said antennae to said receiver, a thermionic vacuum tube individually coupling said receiver with each of said energy feed lines, the input circuits of said tubes being connected across said lines and the output circuits of said tubes being in circuit with said receiver, a phase and amplitude regulation element connected between each tube and said receiver, a surge impedance across each line, and another receiver coupled to said lines in a manner identical with said first receiver.

ALBRECHT GOTHE.
